Application May 8, 1931, Serial No. 536,066

9 Claims. (Cl. 40—125)

The invention relates to a collapsible display device of the type in which a length of flexible material is adapted to be rolled or wrapped about a rod or roller to constitute a compact construction, economizing in space for storing and transportation and which can be readily distended with the flexible material stretched taut.

The primary object of the invention is to provide a simplified form of construction of the type outlined which will feature a high degree of compactness; the utilization of the least possible amount of material and at the same time to give the requisite structural strength to the construction as a whole.

Still another object of the invention and still featuring compactness in construction is to provide a simple means for bracing the structure against distorting strains and to provide for a wide spreading form of base support for holding the stretched material in upright position.

Various other objects and advantages of the invention will be in part obvious from an inspection of the accompanying drawing and in part will be more fully set forth in the following particular description of one form of mechanism embodying the invention, and the invention also consists in certain new and novel features of construction and combination of parts hereinafter set forth and claimed.

In the accompanying drawing:

Fig. 1 is a view in rear elevation showing a preferred embodiment of the invention distended to show it in its operative position and with the parts broken away;

Fig. 2 is a vertical sectional view taken on the line 2—2 of Fig. 1 and looking in the direction indicated by the arrows;

Fig. 3 is a detailed sectional view taken on the line 3—3 of Fig. 2 and showing the stretcher about to be slid into the roller bar; and

Fig. 4 is a view in elevation of the structure shown in the preceding figures rolled in collapsed and housed position.

Referring to the drawing there is disclosed a length 10 of flexible material which may be paper, fabric, or any other material usually used for display purposes such as are used for charts, maps and texts, such as advertising matter.

The upper edge of the material 10 is permanently braced by means of an upper brace 11, one side 12 of which is flat and to this flat side is permanently secured as by gluing or tacking the upper edge of the material 10.

At the lower edge of the material 10 there is secured a similar brace for giving rigidity to this

portion of the fabric. This brace, hereinafter referred to as roller 13, is of somewhat elliptical form as shown in Fig. 2 with a flat side 14 to which the lower edge of the fabric 10 is secured. At the central portion of the underside of the brace 11 there is provided a socket 15 and similarly the roller 13 is provided with an opposing socket 16. A stretcher 17 is positioned with its opposite ends inserted respectively in the sockets 15 and 16 and the parts are so proportioned that the stretcher will hold the flexible material taut when in the distended position shown in Figs. 1 and 2. The stretcher is formed of two parts, a tubular part 18 and a rod 19; the rod 19 being provided adjacent one end with a collar 20 and positioned between the collar 20 and a bead 21 formed on the adjacent end of the tube 18 is a distendable spring 22. It will be noted from the construction as shown in Figs. 1 and 2 that the spring 22 acts to force the parts 18 and 19 in opposite direction thus placing the flexible material 10 under spring tension. The stretcher is so arranged that when the parts 18 and 19 have been demounted from each other the long upper portion 23 of rod 19 may be reversed from the position shown in Fig. 1 and telescoped within the open end of tube 18 so that the telescoped parts are reduced in length and the parts are so proportioned that when so telescoped they may be contained within the bore 24 which extends axially through the roller 13.

To one side of the bore the portion of the roller opposite the flat side 14 is provided with a groove 23 in which is contained or at least partially contained a foot 26, the end adjacent the socket 16 being pivotally mounted in place on pin 27. Instead of this pivotal mounting of the foot 26, it is obviously within the scope of the disclosure to provide a transversely extending bore or socket 28 indicated in dotted lines in Fig. 2 into which the end of the foot may be positioned with a friction tight fit when it is desired to have the foot extend laterally from the roller to obtain the wide spreading support to the device as a whole as indicated in the showing in Fig. 1.

In operation and assuming the parts to be in the position as shown in Fig. 1, it is apparent that the flexible material 10 is stretched taut in its plane to expose the characters on its front side and that when so positioned the material 10 acts to conceal its bracing parts positioned at the rear of the material. There will usually be sufficient play in the flexible material to permit the removal of the stretcher 17 and for this purpose it is noted that the socket 15 is comparatively

shallow. Should difficulty be experienced in removing the stretcher, it is simply necessary to hold two parts of the same and by moving the parts towards each other and against the resistance of the spring 22, one or the other end of the stretcher may be readily removed from its associated socket. When the stretcher is dismounted, the foot 26 is either swung back into position housed within the groove 25 or, in case 10 the socket form of support is provided for the foot, it is simply withdrawn longitudinally from the associated socket at 28 and positioned in the groove 25. The two parts of the stretcher are then separated, reversed and retelescoped as 15 hereinbefore indicated and the telescoped assembly is then inserted in the bore 24, as indicated in Fig. 3. The length of flexible material 10 is then wrapped about the roller in the manner of a shade roller as shown in Fig. 4 and preferably 20 the parts are so proportioned that the flat side 12 of the upper brace 11 will face with the flat side 14 of the roller 13 so that there is finally obtained the smooth, somewhat elliptical wrapped construction shown in Fig. 4 and which may be 25 readily contained in a mailing tube or other container.

By means of a device of this character it is possible to provide a form of display device which can be made much larger than similar constructions now known; which will have a neat, substantially rigid appearance when distended into stretched position and which can be provided with a long supporting foot which will tend materially to one side to maintain the structure supported in its upright display position. When rolled for storage or transportation, there is presented a neat package without projections which might catch in other articles with similar projections and there is provided a structure which 30 can be easily handled and quickly mounted in position thus providing an article which is particularly adapted for lecture and other purposes where different charts and display matter have 35 to be quickly set and dismounted, one after the 40 other.

The present disclosure particularly features a structure which when in wrapped position is entirely self-contained and forms a compact package.

50 I claim:

1. A collapsible display device, comprising a rectangular length of flexible material, a half-round upper brace to the flat side of which is secured the upper edge of the material, a roller 55 having a flat side to which is secured the opposite edge of said material, said upper brace and roller provided centrally thereof with opposing stretcher receiving sockets, a spring distendable stretcher having its opposite ends fitting in 60 said sockets and adapted to stretch the flexible material taut between the upper brace and roller, said stretcher comprising two parts, one adapted to be telescoped within the other when dismounted from its material stretching position, said 65 roller provided with a groove, a foot having one end pivoted to the roller and adapted to be folded into the groove and said roller provided with a bore adapted to receive the two parts of the telescoped stretcher.

70 2. In a collapsible display device, comprising a length of flexible material, an upper brace for stiffening one edge and roller for stiffening the opposite edge and about which the length of flexible material may be rolled, a demountable 75 stretcher adapted to be positioned between the

brace and roller for mounting the flexible material in taut position, said roller provided in an exposed side with a longitudinally extending groove and a foot having one end pivoted to the roller in one position contained in the groove and thus contained within the flexible material when wrapped about the roller and said foot in another position extending at right angles to the length of the roller to provide a laterally extending supporting brace for the device.

80 3. In a collapsible display device, the combination of a roller having a flat side, a flexible member secured along one edge to said flat side, the part of the roller opposite said flat side provided with a groove, a foot pivoted to the roller and adapted to be contained in said groove and said roller provided with a longitudinally extending stretcher containing bore positioned between the groove and the flat side.

85 4. In a collapsible display device, including a length of flexible material, means for holding the material in stretched position, said means including a brace fastened to one edge of the material and a roller fastened to an opposite edge of the material and provided with a bore and also including a stretcher formed of two unequal parts adapted to be positioned centrally between the brace and roller telescoped with one part into the other, the shorter part provided with a spring adapted when the parts are in their 90 distended telescoped relation with the spring interposed between the part acting to hold the flexible material distended and adapted when the parts are reversed in collapsed position with the spring end of the shorter part projecting beyond the longer part to be contained as a whole 95 within the bore.

100 5. In a collapsible display device, comprising a length of flexible material, means for holding the material in taut position, said means including a roller about which the material may be wound, said roller provided with an axially extending bore adapted to contain a part of said means and said roller provided on one side with a groove, and a rod adapted in one position to be 105 contained in the groove, pivoted to the roller and adapted to be disposed in position extending laterally from the length of the roller to provide an offset support for the device.

110 6. In a collapsible display device, comprising a length of flexible material, means for holding the material stretched in taut position, said means including a brace secured to one edge of the material and provided centrally thereof with a socket, a roller secured to an opposite edge of 115 the material and about which the flexible material may be wrapped, said roller provided centrally thereof with a socket facing the socket in the brace and said roller provided axially thereof with a bore open at one end and a spring 120 pressed stretcher adapted to have opposite ends inserted in the opposing sockets and when demounted therefrom adapted to be inserted into the bore through said open end.

125 7. In a display device, the combination of a flexible member, means for holding the same in stretched position, including a lower bracing member, said member provided with a longitudinally extending groove, a foot adapted to be contained in said groove, and adapted to be disposed in position with one end secured to the bracing member at the groove and extending laterally from the bracing member and coacting therewith to provide a wide spreading support 130 for the device.

8. A combined mailing and display poster comprising a flexible body portion, collapsible means for supporting said poster in display position, and a rigid member at each end of the flexible body portion and with which the supporting means is adapted to engage, one of said rigid members being of tubular form to provide a mailing tube for the poster and the collapsed supporting means.
9. A collapsible display device including a flexible display sheet, a pair of opposite edges of which have reinforcing members secured thereto, a stretcher engaging said members and including two rods telescoped one within the other, the portion of one rod slideable within the other being limited by a shoulder on the rod, and a spring surrounding the shouldered rod and interposed between the shoulder and the end of the other rod to stretch the flexible sheet, and a prop for the device attached thereto.

10 9. A collapsible display device including a flexible display sheet, a pair of opposite edges of
